US00D587203S

(12) **United States Design Patent**
Dennes et al.

(10) **Patent No.:** US D587,203 S
(45) **Date of Patent:** ** Feb. 24, 2009

(54) **ELECTRICAL CONNECTOR**

(75) Inventors: **Wayne William Dennes**, Wyoming
(AU); **Jeffrey Allan Glen**, Brichgrove
(AU)

(73) Assignee: **ADC GmbH**, Berlin (DE)

(**) Term: **14 Years**

(21) Appl. No.: **29/297,083**

(22) Filed: **Nov. 2, 2007**

(30) **Foreign Application Priority Data**

May 7, 2007 (AU) 17758/2007

(51) **LOC (9) Cl.** 13-03

(52) **U.S. Cl.** D13/133; D13/139.1

(57) **CLAIM**

The ornamental design for the electrical connector, as shown and described.

DESCRIPTION

FIG. 1 is a front view of an electrical connector showing our design;

FIG. 2 is a rear view thereof;

FIG. 3 is a first side view thereof;

FIG. 4 is a second side view thereof;

FIG. 5 is a first end view thereof;

FIG. 6 is a second end view thereof; and,

FIG. 7 is a perspective view thereof.

The broken line portions of FIGS. 3 through 7 are included to show unclaimed internal subject matter only and form no part of the claimed design.
